Primary Examiner — Catherine Tuttle(74) *Attorney, Agent, or Firm* — 1st-Tech-ideas: Haim M. Factor(57) **CLAIM**

The ornamental design for a portable spraying device, as shown and described.

DESCRIPTION

FIG. 1 is a front and left perspective view of a portable spraying device showing my new design;

FIG. 2 is a rear view thereof;

FIG. 3 is a front view thereof;

FIG. 4 is a left view thereof;

FIG. 5 is a top view thereof; and,

FIG. 6 is a bottom view thereof.

The broken lines are included for the purpose of illustrating the portions of the water toy that form no part of the claimed design.
